UNITED STATES PATENT OFFICE.

FEARING S. THOMPSON, OF SPRINGFIELD, ILLINOIS.

MULTIPLE SPACER.

Application filed January 25, 1926. Serial No. 83,496.

My invention relates to devices adapted to be used for marking off a plurality of positions for rivets or the like all at the same time, an object being particularly in this 5 device to be able to make optional adjustment in the space relation between markers whereby the adjustment of the space relation between any two markers will automatically set all other markers simultaneously to the same space thus providing a uniform space between all markers on the spacer.

I attain the objects of my invention with the device described in the annexed specifications, recited in the claims, and illustrated in the accompanying drawings, in the study of which the above and other objects may become apparent with the description below in which like reference numerals denote 20 like parts in the several figures.

Referring to the figures:

Figure 1 is a top or plan view of the multiple spacer of my invention showing that it is arranged in the form of an extension 25 apparatus and adapted to be lengthwise adjustable.

Figure 2 is also a top extended view of the multiple spacer of my invention showing the spur markers connected therewith arranged in uniform spaced relation and also showing a measuring device connected therewith for optionally spacing the marker 30 spurs to any desired space apart.

Fig. 3 is a side view showing the measuring attachment bracketed to one corner of the spacer and arranged in a position to make suitable adjustment of the spacing between the spur markers.

Figure 4 is a detail showing the winged 40 nut clamp adapted to hold the spacer substantially into any desired predetermined position of adjustment.

Figure 5 is a detail of one of the spur markers adapted to be used also as a pivotal joint at one of the connections.

Figure 6 is a detail showing how the frame members are pivotally connected along one side by means of a tubular rivet in each joint whereby the same may be used as 50 markers also.

Referring in detail to the drawings a plurality of frame members —1— are pivotally connected at the ends with a similar group of frame members —2— and connected 55 along one side of the spacer by means of tubular rivets —3— and along the opposite

side of the spacer at the respective joints by means of a plurality of spur markers —4— which are adapted to serve not only as pivotal connection between corresponding ends 60 of frame members —1— and —2— but also adapted to provide suitable means for marking off positions on sheet metal or drawing paper or other places of the like to designate positions for rivets or bolts or the like. 65

By referring to Fig. 1 it will be noted that between the respective ends of the parallel frame members —1— are arranged in spaced relation suitable rivets —5— and —6— adapted to pivotally engage said 70 frame members with corresponding positions on parallel frame members —2— which are angularly disposed with respect to their relative operating position with frame members —1—. 75

At one end of the spacer pivotally attached to the spacer is a measuring scale —7— adapted to be optionally swung pivotally into a position for taking readings of the space existing between the marking 80 spurs —4— and it will be seen that as a result of the extension feature of the spacer and the pivotal connections between the oppositely disposed groups of frame members —1— and —2— that when any two marking spurs are adjusted to a desired space apart that by making such adjustments in the spacer where thumb screws —8— may be tightened to hold the adjustment in place, all other marking spurs on the same 85 side of the spacer are thereby automatically adjusted to the same space apart and the spacer therefore becomes an accurate multiple spacer adapted to be used for marking off locations for rivets on sheet metal or structural steel or in carpenter work or for designating a plurality of like spaces on a drawing or many other purposes for which this spacer could be used. 90

It will be noted that it would be possible 100 to connect the frame members of this spacer at each joint with tubular rivets like those designated by numeral —3— and in this connection could be used to mark off uniform spaces by sticking a pencil through the 105 hole in the rivet to mark on the surface to be spaced.

To those skilled in the art it will be evident that certain minor changes might be made in the specific structure of the frame 110 members or the marking spurs or other little details but the preferred arrangement there-

for is illustrated in the drawings and has been hereinabove described.

Having thus described the nature of my invention what I claim as new and useful 5 and desire to secure by Letters Patent is:

1. A multiple spacer comprising a plurality of pivotally adjustable frame members, arranged in angularly disposed opposite parallels; one group of said parallel 10 members comprising members spaced apart in ever-parallel space relation; said parallel members of one group each pivotally connected at uniformly spaced predetermined points along its length with pivot points on 15 members of said opposite angularly disposed group of parallel members; said parallel members pivotally engaged by a plurality of holding members at intermediate points along their length and at their end connections, along one side of the spacer, and provided with marking spurs at the end connections along the opposite side of the spacer; 20 said spacer provided at one end with a bracketed, pivotally adjusted measuring

scale for adjusting said marking spurs along the length of the spacer to any desired position of spaced relation.

2. A multiple spacer of the character described including a plurality of frame members operatively connected pivotally; said members comprising two groups of ever-parallel but variably spaced blades pivotally connected at uniformly spaced points along their length with a second group of similar 30 blade members ever-parallel with each other, variably spaced but angularly disposed from said first group; a plurality of marking spurs pivotally secured along one side of said spacer and a measuring scale pivotally bracketed to one end of said spacer extending under adjacent marking spurs; whereby 35 a plurality of points may be located and indicated at equal distances apart simultaneously.

In witness whereof I hereunto set my hand this 14th day of November A. D. 1925.

FEARING S. THOMPSON.
